UNITED STATES PATENT OFFICE.

JAMES E. CLOUGH, OF LA GRANGE, AND WILSON H. STILWELL AND ARTHUR R. FUGINA, OF LOUISVILLE, KENTUCKY.

RAIL-CONTACT CIRCUIT CONTROLLER.

Application filed October 11, 1924. Serial No. 743,102.

To all whom it may concern:

Be it known that we, JAMES E. CLOUGH, WILSON H. STILWELL, and ARTHUR R. FUGINA, all citizens of the United States, the 5 said JAMES E. CLOUGH residing at La Grange, in the county of Oldham and State of Kentucky, and the said WILSON H. STILWELL and ARTHUR R. FUGINA each residing at Louisville, in the county of Jefferson and 10 State of Kentucky, are the joint inventors of certain new and useful Improvements in Rail-Contact Circuit Controllers, of which the following is a specification.

Our present invention relates to improvements on the device described in our former 15 Patent No. 1,312,101 of August 5th, 1919, and relates to means for controlling electric circuits, adapted to be actuated upon the depression of a rail by a passing train, 20 which when primarily actuated upon the passing of a train in either direction, will not be changed by subsequent depressions of the rail, until the train has passed beyond the zone of the device, and which consequently 25 may be used on single track railways.

This invention as set forth broadly in the above named patent also applies to our present invention, which only differs in the improved 30 specific combinations and constructions herein specifically pointed out in the description in the specification and in the drawings, and consists, essentially as set out in the original patent above mentioned, in the combination with a railway track, having points disposed a spaced distance apart, 35 in a rail thereof, and arranged to be depressed by each wheel passing along the rail, of circuit closing means positioned intermediate the 40 depressible points, and having mechanically operable connections therewith.

An object of the invention is to provide circuit controlling means of the character described, having a plurality of connections 45 with a railway rail, and adapted to be actuated from a normal position, by an impulse received upon a depression of the rail at either of said connections, subsequent impulses due to a depression at either of said 50 connections prior to a return to normal, tending to maintain the position assumed in obedience to the primary impulse.

In the accompanying drawings forming part of this specification:

Fig. 1 is a plan view of a portion of a rail-way track showing an embodiment of the invention installed in connection therewith, the cover of the control box being removed, 55

Fig. 2 is a side elevation of the same with the box cover in place, 60

Fig. 3 is a side elevation (on an enlarged scale) of the spring plate in position,

Fig. 4 is a diagrammatic plan of the spring plate in position,

Fig. 5 is a plan view, with cover removed, 65 of the control box containing the selective mechanism,

Fig. 6 is a section on line 6—6 of Fig. 5,

Fig. 7 is a section on line 7—7 of Fig. 6,

Fig. 8 is a section on line 8—8 of Fig. 5,

Figs. 9, 10, 11, and 12, are each front elevations of the essential parts of the selecting mechanism showing their successive positions during a cycle of operation in one direction, and,

Figs. 13, 14, 15, and 16, are each front elevations of the essential parts of the selecting mechanism showing their successive positions during a cycle of operation in the opposite direction.

Referring now to the drawings, therein is shown a portion of a railway track, comprising a rail 11, of conventional design which is secured to cross ties or sleepers 12, by suitable means. Tie plates 13, are secured to certain of the ties, and spring plates 14, are positioned between the tie plates and the rail, at right angles to the rail. The spring plates have a central arched portion 15, which yields under the weight of passing rolling stock, permitting a depression of the rail of $\frac{3}{8}$ of an inch more or less. Each spring plate is retained in place by suitable means such as bolts 16, which pass through slots 17, extended in from the ends thereof, which permit extension of the plate as it flattens out, and through openings in the tie plate.

At a suitable point along the track a weatherproof controller box 19, is positioned, preferably between two cross ties, where it is supported by suitable means such as bars 20, in such a manner that the top of the box will be below the top of the adjacent rail. The box is provided with a removable cover 21. A suitable packing is placed in a space 22, between the cover and the upper edge of the walls of the box to

prevent the entrance of moisture. Pairs of oppositely disposed ears 23, 24 are secured to the sides of the box.

A locking arm 25, is pivotally connected 5 to ear 23, and an eye bolt 26 is pivotally connected to the ear 24. The cover may be secured in place by folding the locking arm there across and engaging eye bolt 26. A nut 27, on the eye bolt is then screwed down 10 against locking arm 25, forcing the cover down upon the box. A hasp 28, which is hinged to nut 27, is then turned down and engaged with staple 29 which is part of eye bolt 26, and a locking element (not shown) 15 such as a padlock inserted through the staple.

An upright plate 30, is erected on the floor of the box and interiorly thereof and transversely thereto which is held in position 20 by having a portion 41, constructed at right angles to the upright section and secured to the floor of the box by suitable means such as bolts 78. Upon portion 41 are mounted insulating blocks 31, which are secured in a 25 horizontal position to portion 41 by suitable means such as screws 32. On blocks 31 are mounted contact springs 33, 35, 37, held in position by and in electrical contact with bolts 34, 36, and 38 respectively, which also 30 serve as binding posts for the attachment of wires (not shown) carrying electric currents to be controlled, these wires entering the controller box through conduit coupling 40. Contact springs 33, 35, 37 bear against 35 and make electrical contact with the surface of metal plates or segments 75, secured to cylinders 76, which are free to turn on their axes, their motion being limited and controlled by cranks 77, which are secured to 40 them. The electric currents are controlled as these cranks are moved or held in position as the case may be by pins 43 projecting from weights 39 and 42 which are pivotally supported by bolt 45, and fall by gravity 45 against the stops 79. Pins 44 which project from weights 39 and 42 protrude through openings 81 and 82 of links 46 and 47 respectively, and bolt 45 through openings 83 and 84 of links 46 and 47 respectively 50 which are pivotally connected by pin 30. These links have hooks 85 and 86 secured to their sides. Secondary levers 48 and 49 are pivotally supported by bolt 45, have secured thereto selector tips 64 and 65 55 respectively and openings 95 and 96 respectively therein. At spaced distances from the controller box, on each side thereof, brackets 50, are positioned, and are secured to the tie plates on which the spring plates 60 are located in proximity to the rails. These brackets comprise parallel spaced walls 51 and 52, joined by an arched portion 53 and a base 54, extended from the wall 52, by means of which they are attached to the tie 65 plates.

A pipe 55, extends along the rail, from the box to the bracket, one end of the pipe being received in a projection or boss 56 on the box and the other end in the wall 51, of the bracket. A shaft 57, is run through the 70 pipe and projects into the boss. The outer end of the shaft is journaled in the wall 52 of the bracket and the inner end in a boss 58 on the inner side of the wall of the box. A dog 59, is secured on the shaft between the 75 walls of the bracket, by suitable means, such as a taper pin, and toe 60, thereof bears upon the flange of the rail. A primary lever 61 is slipped on each of the shafts, the opposite ends the levers 61 being inserted in slots 95 80 and 96 of secondary selector levers 48 and 49 respectively and adjusting dogs 70 and 71 are then secured to the ends of these shafts by suitable means such as a taper pin or a bolt 62, the object of these dogs being 85 to prevent the primary levers from turning on the shafts. A set screw 73 and a check nut 74 are secured to adjusting dogs 70 and 71 for adjusting purposes. A pin 66, erected on the floor of the box extends upward 90 and a spring 68, disposed about the pin and bearing respectively against the floor and in the socket 67 which is secured to the lower side of the primary lever tends to force the latter upward. This movement is resisted 95 by the dogs 59 which bear upon the rail. The arrangement is such that the movement of the levers is controlled by the deflection of the rail which in turn is actuated by the passage of the rolling stock. The relative positions of the dogs 59 and the primary levers 61 on the shafts is such that when the rail is 100 in its normal, or elevated position, the primary levers are in their lowest position.

As a train approaches the apparatus, say in the direction of arrow A, the weight thereof overcoming the tension of the spring plate depresses the rail whereupon the dog at that point being free to move, the spring 68 will force the corresponding primary lever upward, moving selector tip 64, which is part of secondary selector lever 48, upward, engaging hook 85, of link 46, as shown in Fig. 10. Then as selector tip 64 continues to move upward, selector link 46 and counterweight 39 are turned on their axis 45 causing link 47, which is secured to link 46 by pivot 80, to slide toward the left.

As the train passes over the plate, on the other side of the box, it depresses the rail at that point and the corresponding primary lever is raised by its spring 68, as is also secondary selector lever 49 with its selector tip 65 but as selector link 47 has moved to the left the selector tip does not engage hook 86. As a result counterweight 42 is not lifted and in turn crank 77 which operates the circuit controller, is not actuated.

When the rearmost wheel of a train passes over the depressible point in the rail on the 130

near side of a selector-box the rail at that point will return to its normal position and through the medium of the dog 59, and shaft 57, will lower the associated lever 61 disengaging it from the selector link 46 which would then endeavor to return to its normal position, due to the action of the counterweight and releasing link 47 which would tend to return to its normal position 10 being prevented however by tip 65 as can be seen in Fig. 12, which is upheld by reason of the train passing over the depressible point on the far side of the selector-box, which controls it. When the rearmost 15 wheel passes over the depressible point on the far side of the selector-box, the selector tip 65 actuated therefrom will be lowered allowing links 46 and 47 to return to their normal positions by action of the counter- 20 weights, ready for actuation by a train approaching from either direction.

Figs. 13 to 16 inclusive show the successive positions of the selectors for a train passing in the direction of arrow C. It will 25 be seen that the movements are identical with those shown in Figs. 9 to 12 inclusive, which have just been described, except that they occur in reverse order and that in this 30 case crank 77 is actuated thus operating the circuit controller. In order to simplify the description only one crank, for operating the circuit controller, has been shown but it is clear that one may be used on each side and in many cases in practice both are necessary 35 while in other cases only one is required.

Our invention is economical in construction and installation, is efficient in operation, and use, it is durable in service and 40 dependable in operation, and possesses a marked degree of utility.

What we claim as new in our invention and desire to secure by Letters Patent is:

1. In apparatus as characterized, a box, contacts therein, a movable segment, a crank, 45 a pair of pivoted counterweights, a pin extending from said counterweights engaging said crank, a pair of slotted selector links secured to said counterweights, secondary selector levers, selector tips, secured to said 50 secondary selector levers, primary selector levers to engage respectively with opposite secondary levers to turn the segment on its axis, shafts to the inner ends of which said levers are secured, a rail adapted to be depressed at points spaced each way from the box and a dog secured on the outer end of each shaft, a toe of the dog bearing on the rail in proximity to the depressible point and opposing movement of the levers except when the rail is depressed. 55

2. In a circuit controller as characterized, a rail adapted to be depressed at given points by passing trains, a plurality of contacts, a segment, a member adapted to rotate said segment, a complementary member not adapted to rotate said segment, means adapted to be brought into engagement with said member to rotate the same and shifting complementary member to prevent other means 60 from engaging said complementary member, and mechanical operative connections between said means and said depressible points in the rail whereby movement of the rail 65 permits functioning of the means. 70

In testimony whereof, we affix our signatures at the city of Louisville, in Jefferson County and State of Kentucky, this 4th day of October, 1924.

JAMES E. CLOUGH.
WILSON H. STILWELL.
ARTHUR R. FUGINA.
